Lawrence M. Michelson, Clayton, Mo., assignor to Duro Chrome Corporation, St. Louis, Mo., a corporation of Missouri

Application March 11, 1948, Serial No. 145,039

Term of patent 14 years

(Cl. D15—8)

To all whom it may concern:

Be it known that I, Lawrence M. Michelson, a citizen of the United States residing at Clayton, county of St. Louis, State of Missouri, have invented a new, original, and ornamental Design for a Stool Seat, of which the following is a specification, reference being made to the accompanying drawing forming a part thereof, in which Figure 1 is a perspective view of a stool seat embodying my new design; Figure 2 is a top plan view thereof; Figure 3 is a front elevational view thereof; and Figure 4 is a side elevational view thereof.

I claim:

The ornamental design for a stool seat, substantially as shown.

LAWRENCE M. MICHELSON.
